UNITED STATES PATENT OFFICE.

THOMAS B. STONE, CLARENCE C. SMITH, AND PRESCOTT A. SMITH, OF CAMPTOWN, PENNSYLVANIA.

BROOM-HOLDER.

SPECIFICATION forming part of Letters Patent No. 504,183, dated August 29, 1893.

Application filed March 15, 1892. Serial No. 425,011. (No model.)

To all whom it may concern:

Be it known that we, THOMAS B. STONE, CLARENCE C. SMITH, and PRESCOTT A. SMITH, citizens of the United States, residing at Camp-
5 town, in the county of Bradford, State of Penn-
sylvania, have invented certain new and use-
ful Improvements in Broom-Holders, of which
the following is a specification, reference being
had therein to the accompanying drawings.

10 This invention relates to certain new and
useful improvements in devices for holding
tools, brooms and other like articles, where it
is desired to have some means for holding the
same whereby they may be readily inserted
15 and removed and still firmly held in the re-
quired position. We so construct the holder
that we obtain the resiliency of the wire
throughout its entire length, and we get a tor-
sional effect which tends to firmly grasp the
20 handle and yet permit of ready separation
of the jaws to permit the insertion of the
handle therebetween. We secure the holder
at opposite ends of its supporting portion with
portions flat and substantially parallel with
25 the board or support, so that when the jaws
are spread they tend to twist the wire that so
lies flat against the board or support and read-
ily assume their normal position after the
handle has been inserted or removed.

30 Other objects and advantages of the inven-
tion will hereinafter appear and the novel
features thereof will be specifically defined
by the appended claim.

The invention is clearly illustrated in the
35 accompanying drawings, which, with the let-
ters of reference marked thereon, form a part
of this specification, and in which—

Figure 1 is a perspective view of our im-
proved holder. Fig. 2 is a sectional detail
40 showing one manner of securing the end of
the wire.

Like letters of reference indicate like parts
in both views where they appear.

In carrying out our invention we take a
45 wire and bend it any suitable way to form
the jaws A A which are arranged in parallel
relation to each other with their outer ends
turned outward from each other to facilitate

insertion of the handle, being on a compound
curve, preferably, and at their inner ends the 50
wires of the jaws are turned at right angles
to the jaws and substantially parallel with
the board or support B upon which it is held.
The arms a are extended in opposite direc-
tions from their junction with the jaws as 55
seen in Fig. 1, and at their extreme outer ends
are held to the board or support B. If the
holder is formed of a single piece of wire the
arms at one end are provided with a bend or
loop a' which is held to the board or support 60
by a staple or eye or analogous device C and
at the other end the ends of the wire are held
in the board as for instance as seen in Fig. 2
where they are shown as driven through the
board and turned parallel with and seated in 65
a recess in the back side of the board. They
may be otherwise held. The ends may be
turned inward toward each other as seen by
dotted lines in Fig. 1 and then driven into
the board or support. The board should be 70
provided with holes as b to receive the screws
or other means employed to secure it to a
wall or other support.

The salient feature of the present invention
is the arrangement of the arms and jaws so 75
that a torsional twist is given to the wire as
the handle is inserted and removed. The
arms lying flat against the board or support
rock or turn in their normal plane and, hav-
ing a long bearing, there is no danger of dis- 80
tortion or breakage. It is preferable though
not absolutely essential that the jaws be ar-
ranged substantially centrally between the
end attachments of the arms as shown in Fig.
1 and the arms of the jaws lie in substantially 85
the same plane as the arms a, whereby greater
strength is attained with lighter material.

What we claim as new is—

The herein described broom holder consist-
ing of the support B and a single piece of wire 90
having at its center a loop a' held to said sup-
port near one end thereof by a staple and the
ends of the wire bent and extended into and
held in said support, the said wire being
formed intermediate of its two points of con- 95
nection with the support with jaws A A ar-

ranged in planes parallel to each other with
their outer ends turned outwardly and arms
a extended at right angles to the said jaws in
opposite directions, uncrossed and lying flat
5 for their entire length against the outer face
of said support whereby rigidity is secured
and the desired torsional effect produced,
substantially as herein shown and specified.

In testimony whereof we affix our signatures
in presence of two witnesses.

THOMAS B. STONE.
CLARENCE C. SMITH.
PRESCOTT A. SMITH.
